US0D1067257S

(12) **United States Design Patent** (10) Patent No.: **US D1,067,257 S**
Watkins et al. (45) Date of Patent: **** Mar. 18, 2025**

(54) **DISPLAY SCREEN WITH GRAPHICAL USER INTERFACE**

(71) Applicant: **Teletracking Technologies, Inc.**,
Pittsburgh, PA (US)

(72) Inventors: **Katy Watkins**, Pittsburgh, PA (US);
Jamie Slater, Pittsburgh, PA (US);
Thomas Havranek, Baden, PA (US);
Scott Jubeck, Sewickley, PA (US);
Jeanne C. Iasella, Pittsburgh, PA (US)

(73) Assignee: **TeleTracking Technologies, Inc.**,
Pittsburgh, PA (US)

(**) Term: **15 Years**

(21) Appl. No.: **29/785,168**

(22) Filed: **May 24, 2021**

(51) LOC (15) Cl. **14-04**

(52) U.S. Cl.

USPC **D14/486**

(57) **CLAIM**

The ornamental design for a display screen with graphical user interface, as shown and described.

DESCRIPTION

The FIGURE is a front view of a display screen with graphical user interface showing the new design.

The broken lines of uneven length show the display screen and form no part of the claimed design.

The broken lines of even length illustrate portions of the graphical user interface that form no part of the claimed design.

1 Claim, 1 Drawing Sheet
